AIR DISTRIBUTOR

Cortland N. O'Day, Port Washington, N.Y.
(185 Madison Ave., New York, N.Y.)
Filed May 22, 1958, Ser. No. 737,125
7 Claims. (Cl. 98—40)

The present invention relates to an air distributor and it particularly relates to an air distributor device in which the air may be regulated to flow outwardly, either transversely or parallelly or obliquely to the face of the wall or ceiling in which the distributor is mounted.

It is among the objects of the present invention to provide a novel air distributor which will be readily constructed of inexpensive materials and may be readily inserted in a wall or ceiling structure to give a desired air distribution effect.

Another object is to provide a readily adaptable air diffuser construction which will be inserted in a wall or ceiling without marring the same or changing the appearance thereof and which will nevertheless determine broadly the control and distribution of incoming conditioning or ventilating air in the enclosure or room in which it is placed.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

In accomplishing the above objects it has been found most satisfactory, according to one embodiment of the present invention, to provide a flaring unit which may be readily detachably secured within the throat on an air duct and be flush at its outer maximum area with the ceiling or wall and which will consist of a plurality of obliquely arranged louvers which may be so positioned as to extend in the same direction or in different directions.

Where two-way distribution is desired, the louvers may extend outwardly from a central bisector toward the sides of the flaring throat, whereas if a one-way distribution pattern is desired, the obliquely positioned elements may extend from one side of the device toward the other side thereof.

In an alternative combination, a four-way distribution effect is achieved by having the obliquely extending members extend toward each of the sides from a median portion. These various arrangements of obliquely outwardly extending louvers or vanes may be arranged so as to give the desired distribution pattern and one unit may be replaced by another in the flaring throat construction.

These louvers should start adjacent the commencement of the flare but should terminate substantially short of the outer face of the device.

An important feature of the present invention resides in the fact that flush with the ceiling or wall there is positioned a perforated plate, desirably having a large number of openings therein, which will be the final control of the distribution of the air pattern.

The plate should have such a plurality of openings that the openings will occupy from 50% to 75% of the area and the face of the plate should be at least $\frac{3}{8}$ to $1\frac{1}{2}$ inches from the outer edges of the obliquely disposed vanes. The plate itself should desirably be of a thin gauge metal so as not to give a side baffle effect to the outflaring air.

It has been found that a 26 gauge metal of a thickness of 0.0188 is preferably employed. Finer gauge metals may also be employed and the thickness of the plate should generally be between 0.01 to 0.022 inch. The

2

plate, however, should be sufficiently stiff that it will not be subject to vibration or bending due to the force of the air, and where there are strong outgoing currents the thickness may be as much as 0.025 to 0.035 inch.

5 Another important factor of the present invention is provision of adjustable, obliquely disposed vane members which desirably should be located at the outside portions of the throat or be in addition to the outermost obliquely disposed louvers or vane elements.

10 Desirably the throat itself, at the base of its flaring portion, may have these adjustable members attached to the base thereof.

15 With the foregoing and other objects in view, the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope 20 of the claims hereunto appended.

In the drawings wherein like reference characters denote corresponding parts throughout the several views:

25 FIG. 1 is a fragmentary perspective lower view of a tiled ceiling, showing the mounting of the air distributor of the present invention.

30 FIG. 2 is a bottom plan view of the distributor of FIG. 1 with the perforated facing plate removed, more clearly to show the construction thereof, upon an enlarged scale as compared to FIG. 1.

35 FIG. 3 is an inside top view of the distributor from the opposite side, as shown in FIG. 2, showing the portion thereon which is connected to the inside conduit or duct system, upon an enlarged scale as compared to FIG. 1.

40 FIG. 4 is a diagrammatic side elevational view of the distributor of FIGS. 2 and 3, showing the manner of mounting thereof in the ceiling and the manner of connection thereof to the duct.

45 FIG. 5 is a transverse sectional view upon the line 5—5 of FIG. 3.

FIG. 6 is a transverse sectional view upon the line 6—6 of FIG. 5.

50 FIG. 7 is a fragmentary transverse horizontal sectional view taken upon the line 7—7 of FIG. 4, upon an enlarged scale as compared to FIG. 4.

FIG. 8 is a fragmentary transverse sectional view upon the line 8—8 of FIG. 4, upon an enlarged scale as compared to FIG. 4.

55 FIG. 9 is a fragmentary transverse diagonal sectional view upon the line 9—9 of FIG. 2, upon an enlarged scale as compared to FIG. 2.

FIG. 10 is an inside top perspective view of the form of an oblique vane or louver construction, showing a four-way distribution pattern, as utilized in the embodiment of FIGS. 1 to 9.

FIG. 11 is an inside top perspective view of an alternative form of arrangement of oblique vanes or louvers, showing the two-way distribution pattern.

60 FIG. 12 is an inside fragmentary perspective view, showing an alternative form of air distributor in which the distributor is mounted upon the duct, rather than upon the ceiling as is true in FIGS. 1 to 11.

65 FIG. 13 is an outside plan view of the distributor of FIG. 12 with the perforated face plate broken away, more clearly to show the interior construction, upon an enlarged scale as compared to FIG. 12.

FIG. 14 is a side elevational view, showing the mounting of the distributor of FIGS. 12 and 13.

70 FIG. 15 is a transverse vertical sectional view upon the line 15—15 of FIG. 13.

FIG. 16 is a transverse sectional view upon the line 16—16 of FIG. 13.

FIG. 17 is a top inside perspective view of the oblique vane or louver construction of FIGS. 12 to 16.

FIG. 18 is a top inside perspective view of an alternative form of a removable oblique vane or louver construction which may be inserted in the embodiment of FIGS. 12 to 16 in lieu of the unit of FIG. 17.

Referring to FIGS. 1 to 10, there is shown a ceiling A having a plurality of sound absorptive tiles mounted therein with an air distributing device mounted in said ceiling in lieu of one of said tiles.

The air distribution unit, as shown in FIGS. 2 to 10, is detachably mounted on an internal duct or conduit system E by means of the inside telescoping throat F.

The inside telescoping throat F has a shallow flaring throat portion G which terminates in a flat flange H parallel to the ceiling and a peripherally transverse flange J fitting in an opening K in the ceiling A.

The internal unit L, which is shown in the form as used in FIG. 10 and which may be replaced by an alternative form of internal unit M, as shown in FIG. 11, is provided with the obliquely disposed, outwardly extending director vanes N, O, P and Q, which extend in four different directions in FIG. 10, or R and S, which extend in two different directions in FIG. 11.

These vanes are mounted upon an interior framework 25 construction T and U, provided with the readily removable mounting strips V and W.

The flaring sides G are desirably provided with the adjustable outside vanes X, which are pivotally mounted so that they may be swung so as to extend transversely 30 across the direction of, or flow outwardly at the peripheral portion of the flaring throat G of the diffuser.

Referring particularly to FIG. 10, there are shown the main bars 20 of the framework upon which are mounted the top transverse members 21 and 22, which 35 carry the outwardly flaring vanes N and P.

These side bars 20 also carry the downwardly flaring vanes O and Q.

The bars 20 are mounted by means of the end tabs 23 upon the attachment bars T and V which have the flexible end portions 25 having the attachment noses or 40 tongues 26.

These noses or tongues 26, as shown in FIGS. 7 and 8, may be received in the slots 27 of the collar portion F of the flaring throat G.

These tongues may be spread when it is desired to remove the units of FIGS. 10 and 11 or to replace these units by inserting a screw driver which will permit the tongue to move to the dot and dash position, as shown in FIG. 7, whereupon the internal units 10 and 11 may be removed.

The flaring throat G has mounted thereon the hinge connections 28, having the mounting plates 29 for the swinging vanes X. These vanes are all about the same depth and length as the oblique louvers N, O, P, and Q, and, as shown in FIG. 2, they extend the full width of the throat and may be adjustably positioned so as to lie against the flaring sides of the throat G or so as to extend transversely across the outflowing stream of air when they are moved inwardly, as indicated by the arrows 30 in FIGS. 5 and 6.

Normally the air directed by the oblique vanes N, O, P, and Q will tend to flow obliquely outwardly along the ceiling, but where the vanes X are turned inwardly, the direction will tend to be more transverse or normal to the face of the ceiling or wall and, by varying the pattern and position of the adjustable vanes X, various patterns of air flow may be achieved.

In the position as shown in FIGS. 5 and 6, the direction of air flow will tend to separate itself from the ceiling or wall more than if the vanes X were turned so as to contact the flaring throat.

The more these vanes are turned away from the oblique position of the louvers to a normal position parallel to the axis 31, as indicated in FIGS. 5 and 6, the greater the 70

tendency of the outflowing air to be perpendicular to the wall and parallel to the direction of the axis, as indicated at 31.

An important feature of the present invention resides in the perforated facing plate Y, which gives a final distribution to the air and finally controls the distribution thereof. This plate is desirably of fine gauge so as not to act as a lateral baffle, and at least 50%, and desirably 60% to 65% of the area should be covered by circular 10 openings, usually of equal diameter and finely spaced over the face thereof.

Square perforations may also be used, as may hexagonal perforations, but the preference is for circular perforations arranged in aligned or staggered rows, with the preferred pattern being shown in FIG. 2. In all cases, at least 50% of the plate Y should be occupied by the circular openings 39 and the gauge of the plate should be 26, or less in the preferred form.

The plate desirably extends over the entire area of the widest portion of the flaring throat G and the periphery of the plate is enclosed over the entire edge thereof by a U cross section lip 40, which holds the plate rigid in position and also receives the attachment screw 41. The plate will fit against the flat portion H and its edge will fit into the recess 42 formed by the grooved ridge around the periphery of the throat.

This ridge connects the flat portion H and the flange portion J and should be flush with the face 44 of the wall A, as indicated in FIGS. 5, 6 and 9.

These openings, as indicated in FIGS. 2 and 9, extend to the edge 45 of the flaring throat portion G and they cause a pattern of air distribution which has been initially formed by the fixed oblique louvers N, O, P and Q and the movable louvers X, to be controlled as it passes into the room or enclosure.

The mounting screws 50, as shown in FIGS. 5 and 6, will detachably secure the inside end F of the throat portion G to the inside of the duct or conduit E, and, if desired, bayonet connections may be utilized to enable the entire flaring unit G, with its attachment portion F and the outside flange J, to be removed.

However, it is sufficient to remove the distribution units 10 and 11 to give the varied pattern and distribution of air with substitution of different vane arrangements N, O, P and Q in the form of FIG. 10, and S and R in the form of FIG. 11. It will be noted that the outer edges of the oblique vanes N terminate at about half the depth of the flaring throat G and do not extend to the perforated face plate Y.

This provides an area between the perforated face plate Y and the ends of the vanes N, O, P, Q and X in which the oblique directional control has an opportunity to stabilize itself before it is then controlled by the limited area of the openings 39, which control it in its flow across the face plate Y.

In general, however, with the vanes X moved back against the sides of the flaring throat G, the air flowing through the face plate Y will tend to take a direction parallel to or at an acute angle to the face of the wall or ceiling. On any side where the plate X is turned toward the axis 31 and away from the flaring portion G, the direction of the air through the openings 39 in the face plate Y will tend to assume a more normal direction to the wall or ceiling.

In this manner, by merely removing the face plate Y through the four corner screws 41, it is possible to shift the position of these control plates, X, as shown in FIG. 2.

On the other hand, to control the vane relationship, the four screws 41 are removed and then, by spreading the nose engagement 26 by screw driver, it is possible to remove the fixed louver or vane unit of FIG. 10 or 11 from its engagement position inside of the portion F and then to replace it with another unit.

It will be noted that the edges of the noses or tongues

are cammed at 32 (see FIGS. 8, 10 and 11) so that when the unit of FIG. 10 or 11 is moved into position the nose portions or engagement portions 26 will be forced into the dot and dash line position of FIG. 7 and then will snap into the slots 27 when they are in proper position.

The entire unit, as shown in FIGS. 1 to 9, gives a most satisfactory control of air distribution and the combination of the oblique, fixed, and movable vanes, together with the perforated face plate, will most satisfactorily take care of the air distribution.

In respect to the second form of the invention, as shown in FIGS. 12 to 18, the ceiling 60 in this instance carries the peripheral flange 61 of the air diffuser 62.

As shown in FIGS. 14, 15 and 16, the peripheral flange 61 has a flat portion 62 fitting directly against the face 63 of the ceiling 60 and it also has a recessed portion 64, which may receive a sealing material. The flaring throat portion 65 may also receive the hinge plates 66, which carry the hinges 67 on which there are mounted the adjustable outside oblique vanes 68.

The perforated face plate 69 may be engaged along its edges by the U cross section edge engagement 70, provided with four corner screws 71, and it should be flush with the face of the outside flange 61. The screen 25 may be of the same construction as shown in connection with the element Y of FIGS. 1 to 9.

The inside throat portions 72 may be held by screws or bayonet connections to the end 73 of the conduit, and the slots 74 are designed to engage the cam shaped nose portions 75 of the units of FIGS. 17 and 18.

As shown in FIG. 17, the oblique vanes 75 all extend in one direction and they are mounted by means of the cross bars 77, the ends of which fit into the slots 78 and the longitudinal bars 79. These ends are turned over to form the tabs 80 which hold the vanes 76 in position.

The end members 81 carry the cam attachment element 75, and the longitudinal bars 79 also carry the downwardly and outwardly extending side vanes or 40 louvers 82.

This unit, as shown in FIG. 17, will primarily direct most of the air in one direction, with the side vanes 82 controlling part of the stream on each side of the main set of vanes 76.

Usually four of the adjacent vanes 68 will also be employed so as to enable adjustment of the flow of air when the screen 69 is removed.

In the alternative form shown in FIG. 18 the side vanes 82 have been removed and all of the vanes 95 will extend in one direction and they will be mounted by the transverse bars 96 on the attachment elements 97. The attachment elements 97 carry the transverse bars 96 by means of the end tabs 98.

In the form shown in FIG. 18 there is an additional vane 99 having the transverse bar 100, which is held in space relationship by means of the members 101. By providing additional vanes 99, additional control may be provided.

It will be noted that FIGS. 17 and 18 provide substantially for opposite control of the air, with the major stream being directed in the direction 102 in FIG. 17 and at 90° thereof at 103 in FIG. 18.

The adjustment vanes 68 may be adjusted to control the normality of the outgoing air with the perforated face plate giving the balance of the outgoing control. The air diffuser of FIGS. 1 to 18 gives a balanced air distribution effect and enables variable inside control with a perforated face plate giving the final control and regulating the air distribution in a wide range from a direction which is parallel to the ceiling or wall to a direction which is normal to the ceiling or wall.

As many changes could be made in the above air distributor, and many widely different embodiments of this invention could be made without departing from the

scope of the claims, it is intended that all matter contained in the above description shall be interpreted as illustrative and not in a limiting sense.

Having now particularly described and ascertained the nature of the invention, and in what manner the same is to be performed, what is claimed is:

1. An air distribution control for the outflowing ventilating or conditioning air from an internal duct system to and through the ceiling of the room and enclosure 10 receiving the air, having an attachment collar attached to the end of the duct system, an outwardly flaring throat, a plurality of obliquely disposed air directing flat metal rectangular vanes in the flaring throat and mounted at one edge thereof at the narrowest portion of the throat and extending obliquely outwardly toward the widest portion of the throat and a perforated outlet plate across the outside of the flaring throat, said perforated plate being flush with the wall and ceiling and said vanes being fixed in the middle portion of the throat and extending from side to side of the throat, hinge connections at the upper edges of the throat between the attachment collar and the flaring throat, means for mounting the hinge connection on the throat, movable vanes carried by said hinge connections, said movable vanes being movable toward and away from the flaring throat, means to carry and support said movable vanes at the narrowest part of the throat, and means to carry and support said plate at the widest part of the throat.

2. An air distribution control for the outflowing ventilating or conditioning air from an internal duct system to and through the ceiling of the room and enclosure receiving the air, having an attachment collar attached to the end of the duct system, an outwardly flaring throat, a plurality of obliquely disposed air directing flat metal rectangular vanes in the flaring throat and mounted at one edge thereof at the narrowest portion of the throat and extending obliquely outwardly toward the widest of the throat and a perforated outlet plate across the outside of the flaring throat, said vanes being carried on a detachable structure and a camming arrangement permitting ready removal and replacement of said vanes in said attachment collar, said perforated plate being flush with the wall and ceiling and said vanes being fixed in the middle portion of the throat and extending from side to side of the throat, hinge connections at the upper edges of the throat between the attachment collar and the flaring throat, means for mounting the hinge connections on the throat, movable vanes being carried by said hinge connections, said movable vanes being movable toward and away from the flaring throat and means to carry and support said movable vanes at the narrowest part of the throat and means to carry and support said plate at the widest part of the throat.

3. An air distribution control for the outflowing ventilating or conditioning air from an internal duct system to and through the ceiling of the room and enclosure receiving the air, having an attachment collar attached to the end of the duct system, an outwardly flaring throat, a plurality of obliquely disposed air directing flat metal rectangular vanes in the flaring throat and mounted at one edge thereof at the narrowest portion of the throat and extending obliquely outwardly toward the widest portion of the throat and a perforated outlet plate across the outside of the flaring throat, said attachment collar providing a readily removable means providing attachment of the throat as well as the vanes from the end of the duct system, said perforated plate being flush with the wall and ceiling and said vanes being fixed in the middle portion of the throat and extending from the side to side of the throat, hinge connections at the outside edges of the throat between the attachment collar and the flaring throat, means for mounting the hinge connections on the throat, movable vanes carried by said hinge connection, said movable vanes being movable toward and away from the flaring throat and means to carry and support said mova-

ble vanes at the narrowest part of the throat and means to carry and support said plate at the widest part of the throat.

4. A ceiling diffuser having a straight inside connecting throat with an axis transverse to the ceiling, an inwardly flaring throat connecting the transverse throat to the ceiling face, a perforated outlet plate flush with the ceiling face, and means to support the plate at the widest part of the throat at the periphery of the plate to cover the widest part of the throat, and a removable parallel obliquely positioned multiple vane unit detachably mounted at the junction of the transverse and flaring throat and having central fixed vanes and outside movable vanes, said vanes being of flat rectangular sheet metal and being mounted at the narrowest portion of the throat, said vanes obliquely directing any air flowing through the diffuser outwardly toward the periphery of the perforated outlet plate, said removable unit having side transversely extending mounting bars with flexible end portions to engage the junction of the transverse and flaring throats, said flexible end portions having triangular end tabs and recesses in said junction to receive said tabs.

5. In a rectangular ceiling outlet air distributor of the type recessed into the ceiling and having its outlet face received in a rectangular opening in the ceiling and with its outlet face in the same plane as and flush with the ceiling, said air distributor having an inlet conduit to the distributor with the outlet end of said inlet conduit being spaced substantially above and having its axis transverse to the ceiling and a downwardly and outwardly

flaring and divergent throat connected at its upper narrowest end to the outlet end of the inlet conduit and at its lower widest end to said rectangular opening in the ceiling, and a plurality of oblique downwardly extending vanes mounted at their upper ends at the outlet end of the inlet conduit and extending downwardly into the divergent throat and being arranged in two groups, a central group of fixed obliquely disposed vanes and a peripheral group of obliquely disposed adjustable vanes, the lower ends of the vanes terminating above the rectangular ceiling opening and short of the sides of the throat, and a perforated face plate closing and extending across the outer end of the divergent throat and located substantially in the plane of the ceiling.

6. The distributor of claim 5, wherein said central group of vanes have a detachable mounting frame and means to detachably mount said frame at the outlet end of the inlet conduit.

7. The distributor of claim 5, said fixed vanes being provided with a mounting frame consisting of a plurality of transversely disposed mounting members and means to detachably position said mounting members at the junction of the flaring throat and the inlet conduit.
